UNITED STATES PATENT OFFICE.

ABRAHAM L. A. HIMMELWRIGHT, OF NEW YORK, N. Y., ASSIGNOR TO THE NEW JERSEY WIRE CLOTH COMPANY, OF TRENTON, NEW JERSEY, A CORPORATION OF NEW JERSEY.

CONCRETE BEAM PROTECTION.

No. 915,295.

Specification of Letters Patent. Patented March 16, 1909.

Application filed August 28, 1908. Serial No. 450,645.

To all whom it may concern:

Be it known that I, ABRAHAM L. A. HIMMELWRIGHT, a citizen of the United States, residing at New York, county of New York, 5 and State of New York, have invented certain new and useful Improvements in Concrete Beam Protection, fully described and represented in the following specification and the accompanying drawings, forming a part 10 of the same.

The object of the present invention is to provide an improved fireproof protection for the webs of metal beams in concrete floor constructions.

15 The invention is especially intended for the deep main beams commonly called girders, but is applicable to beams of any depth.

It is now common in fireproof buildings to employ a layer of concrete on each side of 20 the beam web, which is usually filled in with and forms a part of the floor concrete, and is usually continued around the underside of the beam to fireproof the beam throughout. It is found in practice, however, 25 that this concrete along the web of the beam is liable to break off, especially in deep beams where the distance between the extended body of concrete at the top of the beam and the body of concrete around the 30 bottom flanges is considerable. This difficulty has not been avoided even by making the concrete on the opposite sides of the web much thicker than is necessary for fireproofing, and moreover such excessive thickness 35 of concrete adds greatly to the weight on the beams, which is very objectionable, especially in long spans.

I provide an efficient protection for the webs of beams of any depth, avoiding all 40 danger of the concrete breaking off and enabling the thickness of the concrete to be reduced substantially to that required for fireproofing, by the use of suitable concrete holding devices extending along the beam 45 web and substantially the full web depth of the beam, by which the concrete is firmly anchored to the beam. The holding devices preferably consist of metal plates on opposite sides of and bolted through the beam 50 web, with anchoring rods extending between the plates. Metallic lathing may be laced to the rods and the concrete protection packed in between the lathing and beam and the finish then applied outside the lathing, or 55 wooden centering may be used in applying

the concrete, and the metallic lathing embedded in the concrete if desired.

In the accompanying drawings forming a part of this specification, I have shown constructions embodying the invention in preferred forms and these constructions will now be described in detail and the features forming the invention then be specifically pointed out in the claims.

In the drawings:—Figure 1 is a vertical 65 section of a portion of a concrete floor, showing a girder provided with my concrete web protection. Fig. 2 is a side elevation of the girder with the holding devices in place, but without the concrete. Figs. 3 and 4 are 70 views similar to Figs. 1 and 2 showing my concrete web protection with woven wire lathing.

Referring to said drawings the beam or girder A is shown as of the common I-form. 75 B is the concrete floor and C the concrete protection for the bottom flanges, this concrete protection C being shown as held onto the bottom of the beam by the clips 10, as in my Letters Patent No. 786,289, dated April 4, 1905.

On opposite sides of the beam web are the bodies of concrete D to fireproof the beam web, this concrete D being held on by the holding devices of my invention. These holding devices in the preferred form shown consist of angle bars 11 extending vertically on opposite sides of the beam web and substantially the full depth of the beam web, as shown, these angle bars being held to the beam by bolts 1 passing through one of their flanges and the beam, so as to hold the angle bars preferably at short distances from the beam web so that the concrete will pack in and anchor between the bars and web. This 85 feature of offsetting the bars from the beam web is not essential, however, as the concrete may be anchored only by the anchoring rods 12, which are passed through openings in the outer flanges of the angle bars 11, so as to be offset from the web sufficiently for this purpose. As shown tie plates 13 are used midway between the angle bars 11, through which plates 13, the anchoring rods 12 are threaded, so as to stiffen the rods between 100 the angle bars and permit the latter to be placed farther apart.

The construction shown in Figs. 3 and 4 is exactly the same as that shown in Figs. 1 and 2, except that metallic lathing, which may be 110

of any suitable form of perforated or reticulated metal, is secured to the rods 12 and embedded in the concrete, woven wire lathing 14 being shown, which is tied to the rods 5 12 by ties 2.

It will be understood that the invention is not limited to the specific form of holding devices shown, nor to the specific construction of floor or beam in connection with 10 which the invention is illustrated, but that these may be varied within the invention as defined by the claims.

What is claimed is:—

1. The combination with a metal beam, of 15 a fireproof protection for the web, consisting of metal plates on opposite sides of the beam secured to the beam web, anchoring rods carried by said plates, and suitable plastic material in which said plates and rods are 20 embedded.

2. The combination with a metal beam, of 25 a fireproof protection for the web, consisting of metal plates on opposite sides of the beam

secured to the beam web, anchoring rods carried by said plates, metallic lathing se- 25 cured to said rods, and suitable plastic material held by said rods and lathing.

3. The combination with a beam A, of vertical plates 11 secured to the beam web, horizontal anchoring rods 12 carried by said 30 plates, and concrete D held by said plates and rods.

4. The combination with a beam A, of vertical plates 11 secured to the beam web, horizontal anchoring rods 12 carried by said 35 plates, metal lathing 14 secured to said rods, and concrete D held on the beam by the rods and lathing.

In testimony whereof, I have hereunto set my hand, in the presence of two subscribing 40 witnesses.

ABRAHAM L. A. HIMMELWRIGHT.
